(57) CLAIM

The ornamental design for a typeface or type font, as shown and described.

DESCRIPTION

FIGS. 1A-1G, 2A-2D, and 3A-3C depict an embodiment of a typeface or type font. In particular, FIGS. 1A-1G depict a first character set of the embodiment, including a version of the alphabet; FIGS. 2A-2D depict a second character set of the embodiment, including certain punctuation marks; and FIGS. 3A-3C depict a third character set of the embodiment, including certain Arabic numerals.

Features shown in broken lines form no part of the design as claimed. Features shown in crosshatching form no part of the design as claimed.
